UNITED STATES PATENT OFFICE.

FREDERICK GASTON, OF PHILADELPHIA, PENNSYLVANIA.

RAILROAD-TIE.

1,322,184.

Specification of Letters Patent.

Patented Nov. 18, 1919.

Application filed January 31, 1919. Serial No. 274,155.

To all whom it may concern:

Be it known that I, FREDERICK GASTON, a citizen of the United States, residing at 6338 Drexel road, Philadelphia, in the 5 county of Philadelphia and State of Pennsylvania, have invented a certain new and useful Railroad-Tie, of which the following is a specification.

My invention relates to ties of a type intended to be made of steel-rolled shapes and concrete and is intended to apply both to the support of the rail and to the construction of the tie itself.

The purpose of my invention is to provide a readily removable resilient rail support for the tie and to combine it with rail-clamping mechanism.

A further purpose is to stiffen the tie without unduly increasing the weight of the 20 tie.

A further purpose is to clamp the rail from above directly against a resilient support.

Further purposes will appear in the specification and in the claims.

I have preferred to illustrate my invention by but one form, selecting a form which is strong, efficient and comparatively inexpensive and which at the same time well 30 illustrates the principles of my invention.

Figure 1 is a top plan view of a portion of a railway track provided with ties embodying my invention.

Fig. 2 is an end view of such a structure 35 as is seen in Fig. 1, showing the rails in sections.

Fig. 3 is a section taken upon line 3—3 of Fig. 1.

Fig. 4 is a perspective view of a tie, omitting the resilient rail supports and clamps.

Fig. 5 is a perspective view of one of the resilient tie supports.

Fig. 6 is a perspective view of one of the clamps used by me.

Fig. 7 is a section upon line 7—7 of Fig. 8 and Fig. 8 a section upon line 8—8 of Fig. 7, both showing the tie immediately about the rail support.

In the drawings similar numerals indicate like parts.

The tie 10 is shown as supporting rails 11 in a track ballasted at 12.

The body or skeleton of the tie is formed as a rolled channeled shape, having upper 55 flanges 13, 13' and lower flanges 14, 14' with intermediate flanges 15, 15', forming upper

and lower channels, on each side shown at 16, 17 and 16', 17' respectively. The web portions between the flanges, I have indicated at 18 and 19. 60

At the positions which are to be occupied by the rail, I cut away the upper flanges 13, 13' and a portion of the web 18 to leave a rib 18' on each side. The block 20 is adapted to fit into the space provided by 65 cutting away the top flanges and web and is grooved at 21 to coöperate with the rib 18', to prevent movement of the block lengthwise of the rail. The block forms a resilient rest or support for the rail which 70 is protected against movement in any direction and is readily replaceable. It can be removed or replaced by but slightly lifting the rail to allow the block to be lifted slightly and then moved longitudinally of 75 the rail (transversely of the tie).

As best shown in Fig. 8, the rail is intended to rest directly upon the block 20 and the block may desirably be coextensive in width with it. The rail is clamped upon 80 the block by clamps 22, 23, which are held in place by bolts 24 passing through openings 25 in the flanges 13 and 13' and 25' in the clamps. The bolts are preferably inserted from below and may be held against 85 turning by engagement of the head 26, with the web 18. Any usual lock nuts may be used.

The parts are so proportioned that the clamps tightly engage the rail when or just 90 before the bottoms of the clamps come against the top of the tie, as seen in Fig. 8, whereby the rail receives the side support of the inner edges 27 of the clamp at the same time that it is tightly gripped between the active clamp faces 28 and the block.

Though my tie may be used without a concrete filling, I prefer using a filling of concrete at 29 which completely closes the 100 channels 16, 17, 16', 17', except as to spaces in the channels 16 and 16' adjacent to the blocks 20. The concrete is omitted not only in the space intended to be occupied by the block, but also from spaces 30 on each side 105 of each block, which spaces are left open for insertion and removal of the bolts 24.

The tie is set as any other tie and, when initially set, the blocks may be inserted from the top and the rails subsequently applied 110 above them. In cases of renewals the old block is removed by slightly lifting the rail

and the block and moving the block lengthwise of the rail until it is free from the rib 18' and can be removed sidewise between the ties. The new block is inserted 5 by merely reversing this operation.

It will be seen that the blocks rest upon the flanges 15, 15' firmly and are protected against longitudinal movement by the ribs 18' and against lateral movement by the 10 adjoining edges of the webs 18.

It will be evident that the blocks afford a great variety of support from the standpoints of firmness, resilience, etc.; that by the use of creosote or other treatment, the 15 block may be effectively protected from decay and from disintegration by the elements; offering a small, handy, cheap replacement for the only perishable part of the tie.

Having thus described my invention, what 20 I claim as new and desire to secure by Letters Patent is:

1. A railway tie comprising a longitudinally extending channeled member providing top flanges and block-supporting flanges 25 and having the upper flanges and the web between the flanges cut away, in combination with a block adapted to lie within the space of the web and flanges where cut away and clamps resting upon the top flanges and 30 adapted to retain the rail upon the block.

2. In a steel tie construction, a steel skeleton having a web, top flanges and supporting flanges, both on opposite sides of the web, the top flanges and web being cut away 35 nearly to the supporting flanges, in combination with fibrous inserts adapted to rest upon the supporting flanges and be retained against movement laterally of the tie by the remainder of the web which is not cut away 40 and retaining devices for the rail secured to the top flanges in the neighborhood of the cut-away portions and adapted to hold the rail down upon the fibrous inserts.

3. A steel tie construction comprising a 45 steel skeleton having top flanges, a web and supporting flanges in proximity to the top flanges, the top flanges and a portion of the web at each side above the supporting flanges being cut away, in combination with fibrous 50 inserts for the rail to rest upon, said inserts resting upon the supporting flanges and receiving the weight of the rail, and clamps resting upon the top flanges and retaining the rail.

55 4. A steel tie construction comprising a tie having central webbing and three flanges on each side thereof, the top flanges and the webbing being cut away to receive an insert, in combination with a fibrous insert adapted 60 to rest upon the intermediate flanges within the cut away portions and receive the weight of the rail.

5. A steel tie construction comprising a tie having central webbing and three flanges 65 on each side thereof, the top flanges and the

webbing being cut away to receive an insert, in combination with a fibrous insert adapted to rest within the cut away portions and receive the weight of the rail and concrete filling for the channels between the 70 flanges.

6. A steel tie construction comprising a tie having central webbing and three flanges on each side thereof, the top flanges and the webbing being cut away to receive an insert, 75 in combination with a fibrous insert adapted to rest within the cut away portions and receive the weight of the rail and concrete filling for the channels between the flanges, the filling being omitted on both sides of 80 the fibrous insert between the top and intermediate flanges on each side.

7. In a steel tie construction, a central web, opposite flanges upon which the tie is adapted to rest, flanges on opposite sides of 85 the web at an intermediate point in its height, fibrous blocks adapted to rest on the intermediate flanges and support the rail and clamps above the blocks securing the rail.

8. A steel tie construction comprising a 90 metal web having three flanges on each side and intermediate channel portions, supports for the rail separate from the web, clamps for securing the rail to said supports and concrete filling for the tie except in proxim- 95 ity to the supports.

9. In a railway tie, a rail-supporting fibrous insert in the form of a block having a notch in the bottom thereof, in combination with a tie forming a support for the 100 block, and having a rib fitting into the notch to prevent movement of the block laterally with respect to the tie, and clamping means engaging the tie and adapted to hold the rail in contact with the fibrous insert. 105

10. A railway tie having a central web and upper flanges cut away at intervals for the insertion of rail-supporting fibrous members, flanges in proximity to the cut-away portions, fibrous inserts adapted to rest upon 110 the flanges and clamps secured to the upper tie flanges and adapted to hold the rail in engagement with the inserts.

11. In a railway tie, a metallic tie skeleton comprising a longitudinally-extending 115 channeled shape having upper flanges and upper web, both cut away to provide for rail-supporting inserts, in combination with fibrous inserts fitting therein, clamps secured to the upper flanges and retaining the rail 120 in contact with the inserts and non-metallic filling for the channeled portion, at a distance from the inserts.

12. A channeled shape comprising a vertically disposed web, and bottom, intermediate and top flanges on each side, extending the length of the tie, but the top flanges and the upper part of the web cut away to leave room for the tie supporting member, leaving ribs at these points from the web por- 125 130

- tion, the upper flanges being apertured to provide holes for retainers, in combination with fibrous rail-supporting members having grooves in their under sides, adapted to 5 rest upon the intermediate flange and have the web ribs rest within the grooves, clamps engaging the rail flanges and retaining bolts inserted within the holes in the flanges and in the clamps and holding the clamps in position.
13. A channeled shape comprising a vertically disposed web, and bottom, intermediate and top flanges on each side, extending the length of the tie, but the top flanges and 15 the upper part of the web cut away to leave room for the tie supporting member, leaving ribs at these points from the web portion, the upper flanges being apertured to provide holes for retainers, in combination 20 with fibrous rail-supporting members having grooves in their under sides, adapted to rest upon the intermediate flange and have the web ribs rest within the grooves, clamps engaging the rail flanges, retaining bolts inserted within the holes in the flanges and in 25 the clamps and holding the clamps in position and non-metallic filling for the channels between these flanges, omitted in proximity to the cut-away portions to permit insertion and removal of the fastening devices.
14. In a railway tie construction, a metallic tie skeleton comprising a central web, oppositely-disposed flanges at the top and bottom and between these points, the top 30 flanges being cut away at intervals, in combination with rail-supporting fibrous inserts located at the cut-away portions, and resting upon the intermediate flanges, and clamps secured to the top flanges adapted to engage the rail and hold it in engagement with the 35 inserts.
15. In a railway tie construction, fibrous rail-supporting blocks, grooved along their under surfaces, in combination with metallic skeleton supports for the blocks, and 40 clamping devices engaging the skeleton and adapted to hold the rails in contact with the blocks.
16. In a metallic tie construction, fibrous rail-supporting blocks in combination with 45 a metal skeleton tie upon which the blocks are adapted to rest, flanged at the top, and clamps each resting at one end upon the skeleton tie and at the other end against the rail base and fastening devices for the 50 clamps between the ends.
17. In a metallic railway tie, a fibrous rail-supporting block, a skeleton tie support for the block, a railway rail, a clamp therefore engaging the rail flange at one end and 55 the tie skeleton at the other end, a bolt passing upwardly through the skeleton tie and clamp, to retain the clamp and filling for the metallic skeleton tie, omitted in proximity to the bolt to give room for its insertion and 60 removal.
18. In a railway tie construction, a metallic tie skeleton comprising a central web, oppositely-disposed flanges at the top and bottom and between these points, the top 65 flanges being cut away at intervals, in combination with rail-supporting fibrous inserts located at the cut-away portions, and resting upon the intermediate flanges, and clamps secured to the top flanges adapted to engage the rail and hold it in engagement with the inserts.

FREDERICK GASTON.
